METAL STUD AND JOIST

Charles E. Dellenbarger and Milton Mannist,
Philadelphia, Pa.; said Mannist assignor to said
Dellenbarger

Application October 28, 1937, Serial No. 171,456

9 Claims. (Cl. 72—115)

This invention relates to improvements in metal studs and joists for use in building constructions.

The object of the invention is to form studs and joists of angle bars forming longitudinal corner members, and transverse braces formed of wire, thereby providing studs and joists which are light in weight and which can be manufactured at a low cost.

10. A further object is to construct wire braces in separate units which may be readily secured to the corner members by welding or brazing.

15. A further object is to construct the wire braces with diagonal members having foot members extending parallel with the corner members and forming with the latter extended welding surfaces for increasing the rigidity of the structure.

20. A further object is to form the braces with central ribs forming part of the diagonal members and secured together in parallel relation by welding together the parallel portions.

25. A further object is to construct wire braces having a minimum number of members, which braces are adaptable for forming light weight studs for vertical walls, or partitions, not subjected to great strains, and to which braces additional members, and diagonal struts may be added for making the braces adaptable for joists for floors and ceilings required to carry greater loads.

30. A further object is to attach the foot members of the braces to the corner members in a novel manner to facilitate in welding the parts.

These together with various other novel features of construction and arrangement of the parts, which will be more fully hereinafter described and claimed, constitute our invention.

Referring to the accompanying drawings:

Fig. 1 is a perspective view of our novel brace adapted for use in the formation of studs.

40. Fig. 2 is a side view of Fig. 1.

Fig. 3 is an end view of Fig. 1.

45. Fig. 4 is a perspective view of a brace with connecting members forming a rectangular structure and including diagonal struts.

Fig. 5 is a side view of a connecting member and strut, detached.

Fig. 6 is an end view of Fig. 4.

50. Fig. 7 is a perspective view of a brace similar to that shown in Fig. 1, and formed of two wires welded together.

Fig. 8 is an end view of a stud embodying the brace shown in Figs. 1 to 3.

55. Fig. 9 is a longitudinal section on line 9—9 of Fig. 8.

Fig. 10 is a longitudinal section on line 10—10 of Fig. 11.

Fig. 11 is an end view of a joist embodying the brace shown in Figs. 4 to 6.

Fig. 12 is a side elevation of the joist shown in Fig. 11, showing a portion thereof in section as on line 12—12 of Fig. 11.

In the drawings, in which like reference characters refer to like parts, 15 represents the brace shown in Figs. 1 to 3. Said brace is formed of a 10 single wire bent upon itself into diagonal members 16, 17, 18 and 19, extending in a common plane. A foot member 20 is formed upon each diagonal member and extends at right angles to said plane. Transverse connecting members 21 and 22 are connected between diametrically opposite pairs of foot members.

Said connecting members 21 and 22 are formed integrally with the opposite ends of the foot members relatively to the diagonal members, and 20 said connecting members occupy a different plane from the plane of the diagonal members, thus forming means for readily placing the brace in a transverse position relatively to the length of the corner members when the braces and corner members are being assembled.

The upper connecting member 22, as shown in Fig. 1, is bent upon itself to form a foot member 23 which is welded to the foot member on the diagonal member 16.

The members 16 and 17 form approximately a right angle having a flat portion 25 at the apex, and the members 18 and 19 are also formed in a similar manner with a flat portion 26. Said flat portions are joined by welding into a central rib 27, thus forming the brace into a rigid structure, with said parallel flat portions 25 and 26 presenting elongated welding surfaces.

Fig. 7 illustrates a brace 29 formed of two separate wires, each comprising diagonal members 30 and 31, with foot members 32 and 33. The foot members 33 are each formed with a transverse connecting member 34, which latter terminates with a foot member 35. The foot members 32 and 35 are welded together at the opposite corners of the brace. The diagonal members 30 and 31 are connected by a flat portion 36. The flat portions 36 of two similar wires are placed parallel to each other and form elongated welding surfaces adapted to be welded into a central rib 37, forming the brace into a rigid structure.

The transverse braces above described are adapted for forming studs 40, shown in Figs. 8 and 9, for use in vertical partitions and walls. Said studs 40 are formed of four parallel, longi-

tudinal, corner members 41, with the braces 15 secured at intervals throughout the length of said corner members. The braces are positioned transversely to the length of the corner members 5 and hold the latter in spaced relation to each other in the form of a rectangular stud.

Each corner member 41 is in the form of an angle bar, and consists of plates 42 and 43 arranged at right angles to each other with the 10 apex of the angle extending outwardly relatively to the center of the stud, as shown in the end view Fig. 8.

The foot members 20 and 23 of a brace, such as shown in Fig. 1, are positioned parallel with 15 the length of the corner members 41 and said foot members are welded to the plates 42, forming welded joints 45. Said foot members provide elongated welding surfaces between the foot members and the plates 42 of the corner bars as 20 shown in Fig. 9, thus increasing the rigidity of the welded joints 45. The foot members extend at right angles to the plane occupied by the diagonal members 16 to 19, and also at right angles to the plane occupied by the connecting members 25 21 and 22, so that each foot member forms a base or foot for rigidly attaching the brace to the corner members, thereby adding rigidity to the diagonal and connecting members and forming a rigid stud comprising a minimum number 30 of parts.

The foot members are attached to one angle plate only of each corner member, as shown in Fig. 8. The foot members of the braces are attached to the plates 42 and are located in 35 spaced relation to the plates 43, thereby providing sufficient room for the application of a welding tool between the joints 45 and the apex of the angle of the plates 42 and 43.

The braces 48, shown in Fig. 4, are adaptable 40 for forming floor joists, and the like, where greater rigidity is required than in the studs. The brace 48 embodied in the joist 50, shown in Figs. 10 to 12, is similar to the brace shown in Fig. 1, with the addition of connecting members 52, which are secured to said brace to form a rigid 45 rectangular frame. The connecting members 52 are each provided with foot members 53 and 54, extending at right angles to the length of said members 52, as shown in Fig. 5. Said foot members 53 and 54 are placed parallel with the foot members 20 and are welded to the latter.

A diagonal strut 56 is formed upon the foot member 54 of each connecting member 52, and said strut terminates in a foot member 57.

The joist 50 includes corner members 41, similar 55 to those shown in Fig. 8, and between which members are secured the braces 48 by welding the foot members to one of the angle plates 42 of each corner member 41, as shown in Fig. 11. The struts 56 extend between adjacent braces 48 and also between two parallel corner members 41, to which the struts are welded as shown in Fig. 10, thus forming the four corner members 60 into a rigid rectangular structure adaptable for use as beams, girders and joists for buildings and like structures.

Various changes in the construction and arrangement of the parts may be made, and the novel braces may be applied to different forms 70 of corner members, without departing from our invention.

We claim:

1. A wire brace for metal studs and joists comprising, diagonal members having central parallel 75 portions secured together and forming a central

rib from the opposite ends of which rib the diagonal members branch in a common plane, foot members upon the diagonal members, said foot members extending at right angles to said plane, and connecting members extending at right angles to the length of the foot members and connecting said foot members. 5

2. A wire brace for metal studs and joists comprising, two wires having parallel portions welded together and forming a rib from the opposite 10 ends of which rib the wires extend diagonally in a common plane, foot members upon the outer portions of the diagonally extending members, said foot members positioned at right angles to said plane, and a transverse member integrally 15 formed with a foot member of each wire and extending at right angles to the length of the foot member and welded to a foot member of the opposite wire.

3. A wire brace for metal studs and joists comprising, diagonal members arranged in pairs, each pair having a flat connecting portion at the apex of the angle formed by said diagonal members, means securing said flat portions into a central rib from the ends of which rib said 25 members extend diagonally in a common plane, foot members upon the outer extremities of said members, and connecting members upon the foot members and positioned to form a rectangular frame embracing said diagonal members. 30

4. A metal stud or joist comprising longitudinal metal corner members, braces formed of wire and positioned transversely at spaced intervals throughout the length of said members, each brace comprising diagonal members, foot members 35 upon the diagonal members and extending parallel with the length of said corner members, transverse connecting members extending between diametrically opposite pairs of said foot members, and means securing said foot members 40 to the corner members.

5. A metal stud or joist comprising longitudinal metal corner members, braces formed of wire and positioned transversely at spaced intervals throughout the length of said members, each 45 brace comprising diagonal members, foot members upon the diagonal members and extending parallel with the length of said corner members, said diagonal members having central parallel portions secured together and forming a central 50 rib from the opposite ends of which rib the diagonal members branch in a common plane, and means securing said foot members to the corner members.

6. A stud or joist comprising longitudinal corner members, diagonal members formed of wire and joined together into a center rib, said diagonal members positioned transversely at spaced intervals throughout the length of said corner members, a foot member upon each diagonal 60 member and extending parallel with said corner members, connecting members attached to said foot members and forming a rectangular frame embracing said diagonal members, and means securing said foot members to said corner members. 65

7. A stud or joist comprising longitudinal metal corner members, braces formed of wire and positioned transversely at spaced intervals throughout the length of said corner members, foot members upon said braces adjacent to each corner 70 member and extending parallel with the latter, struts positioned obliquely to the length of said corner members and extending between foot members of adjacent braces, and means securing said foot members to the corner members. 75

8. A stud or joist comprising longitudinal corner members formed of metal angle bars, diagonal members formed of wire and joined together into a center rib, a foot member upon each 5 diagonal member and extending parallel with said corner members, connecting members attached to said foot members and forming a rectangular frame embracing said diagonal members, struts attached to diametrically opposite 10 foot members and extending obliquely to the length of corner members, a foot member upon the opposite end of each strut and extending parallel with said corner members, and means attaching said foot members to said corner members. 15

9. A metal stud or joist comprising longitudinal corner members each formed of two integral plates positioned at right angles to each other, a wire brace positioned in a plane at right angles to the length of the corner members, foot members upon said brace extending parallel with the length of said corner members, and means securing the foot members to the medial portion of the inner surface of a plate of each corner member 10 and in spaced relation to the apex of the angle formed by the adjacent plates of the corner members. 5
